CLAIM

I claim the ornamental design for a face mask for playing musical instruments, as shown and described.

DESCRIPTION

FIGS. 1-7 illustrate a face mask for playing musical instruments, in which:

FIG. 1 is a perspective view of the face mask for playing musical instruments in use;

FIG. 2 is a front view;

FIG. 3 is a rear view;

FIG. 4 is a top view;

FIG. 5 is a bottom view;

FIG. 6 is a right-side view; and,

FIG. 7 is a left-side view.

The human form and musical instrument illustrated in broken lines in FIG. 1 represent environment during usage only and form no part of the claimed design. Features of the face mask for playing musical instruments illustrated in broken lines represent no part of the claimed design.

1 Claim, 7 Drawing Sheets
